United States Patent Office.

NICHOLAS S. VEDDER, OF TROY, NEW YORK.

Design No. 2,737, dated August 6, 1867.

DESIGN FOR THE PLATES OF A STOVE.

The Schedule referred to in these Letters Patent and making part of the same.

TO ALL WHOM IT MAY CONCERN:

Be it known that I, NICHOLAS S. VEDDER, of the city of Troy, in the county of Rensselaer, and State of New York, have invented or produced a new and original Design for Plates of a Stove, of which the following is a full and exact description, reference being had to the accompanying photographs of the door-plate and upper and lower end plates of an oblong or oval stove.

The design of the door-plate A, shown by fig. 1 on a different scale from the other photographs, consists of a central ornament, b, a surrounding moulding, c, and border mouldings, d e, all shaped and arranged on the curved and ornamental form of that plate, so as to appear as represented in fig. 1. The design of the end plate F consists of three central ornaments g g g in panels formed by ornamental mouldings h, all shaped and arranged on the curved surface of the plate so as to present the appearance represented in fig. 2; and the design of the end plate I consists of the centre ornament j and the surrounding ornamental mouldings k, l, and m, all shaped and disposed on the curved surface of the plate, so as to appear as represented in fig. 3.

What I claim as my invention or production, and desire to secure by Letters Patent, is—
The ornamental design of the plates A, F, and I of a stove, as shown and described.

NICHOLAS S. VEDDER.
